(57) **CLAIM**

The ornamental design for a “stirrup cover,” as shown and described.

DESCRIPTION

FIG. 1 is a bottom plan view of a stirrup cover according to my design;

FIG. 2 is a side elevational view thereof;

FIG. 3 is a front elevational view thereof;

FIG. 4 is a back elevational view thereof;

FIG. 5 is a top plan view thereof;

FIG. 6 is a side elevational view thereof with a stirrup entering the cover;

FIG. 7 is a side elevational view thereof with a stirrup in the cover and a boot poised to enter the back of the cover and through the stirrup; and,

FIG. 8 is a side elevational view thereof with the cover and stirrup having received the boot.

The dashed lines illustrated in the drawings of FIGS. 6–8 illustrate a stirrup with which the cover is used and a boot entering the cover and stirrup, and do not form any part of the invention for which design patent protection is sought.
